(57) **CLAIM**

The ornamental design for a slicer, as shown and described.

DESCRIPTION

FIG. 1 is a front, left, top perspective view of a slicer in the first state, showing my new design;

FIG. 2 is a rear, right, bottom perspective view thereof;

FIG. 3 is a front, right, top perspective view thereof;

FIG. 4 is a front elevational view of the enlarged scale thereof;

FIG. 5 is a rear elevational view of the enlarged scale thereof;

FIG. 6 is a left side view of the enlarged scale thereof;

FIG. 7 is a right side view of the enlarged scale thereof;

FIG. 8 is a top plan view of the enlarged scale thereof;

FIG. 9 is a bottom plan view of the enlarged scale thereof;

FIG. 10 is a front, left, top perspective view of a slicer in the second state; and,

FIG. 11 is a front, left, top perspective view of a slicer in the third state.

The dashed broken lines in the figures illustrate portions of the slicer that form no part of the claimed design.
